MANUFACTURE OF CIGARETTES

Arthur Bingham, Deptford, London, England,
assignor to Molins Machine Company, Limited,
London, England

Application August 24, 1936, Serial No. 97,707
In Great Britain October 4, 1935

11 Claims. (Cl. 131—39)

This invention is for improvements in or relating to the manufacture of cigarettes, and refers more particularly to a method of and a machine for making cigarettes, provided with filter plugs, 5 mouthpieces or the like.

The mouthpieces shall for convenience be referred to herein as stubs, and the term "stub" shall include mouthpieces in the form of tubes of paper or other material which may be empty, 10 or filled entirely, or partly with filtering or flavouring material or tobacco. It will be appreciated that where the tubes are not filled they should have sufficient rigidity to enable them to remain open when the cigarettes are 15 being smoked.

The term "stub" shall also be deemed to include a composite mouthpiece constituted in part by a length of wrapped cigarette rod, and in part by a length of filter or flavouring material wrapped in a tubular wrapper or by a tubular piece which is either hollow or partly filled with filter or flavouring material. The term "stub" shall also be deemed to include a mouthpiece comprising a length of tobacco filler in a wrapper, 20 which tobacco is of a different kind of tobacco from that forming the main body of the cigarette.

Cigarettes provided with stubs will, for convenience, be referred to herein as "mouthpiece cigarettes."

It is found when a plurality of stubs is fed in a manner such that the stubs are in axial alignment and abutting end to end, that when it is desired to separate the stubs, the stubs tend to adhere to each other, due to a number of causes. 30 Sometimes the stubs are not uniform in shape, and they may, for example, be oval in shape, in which case it is often found during the feeding of the stubs that when the stubs are considered in a single plane, the major axis of one stub is at right angles to the major axis of the adjacent stub. When this occurs, difficulty is invariably experienced in satisfactorily feeding the stubs.

Difficulty is also experienced when the stubs are formed from paper or other filter material, such 45 for example as layers of crepe paper between which there are placed layers of cellulosic material. It is found, when the stubs are formed from such material, that frequently a portion of material projects from the end of a stub, and that when the stubs are abutting, the projecting portions from one stub become entangled with the end of the adjacent stub. This difficulty is more particularly noticeable when the stubs are fed from a hopper in the form of comparatively 50

long lengths of stub material which are severed into desired lengths for uniting with cigarettes.

According to the present invention there is provided in or for a machine for manufacturing mouthpiece cigarettes by uniting aligned adjacent stubs and cigarettes by securing wrapping material to or around said adjacent stubs and cigarettes whilst said stubs and cigarettes are moving axially, apparatus comprising means for feeding a plurality of axially aligned stubs which 5 have ends abutting or closely adjacent, and means operative to space said stubs apart from each other in the direction of their longitudinal axes.

The spacing of the stubs may be repeated or effected in a plurality of stages, and between the 15 repeated spacing or stages means may be provided to align the stubs with respect to the path which they followed before the separating operation and the means may be operative to move the stubs in the direction of their longitudinal axes and towards the central point of their combined overall 20 length.

The stubs may be fed by a conveyor, and a guide element or elements provided to engage with the stubs to space the stubs apart from each 25 other in the direction of the longitudinal axes. The conveyor may comprise a rotatable drum having flutes in its periphery for the reception of the stubs and a guide may be provided for each stub, the guide extending around or partly 30 around the periphery of the drum. The guides are disposed at varying distances from the periphery of the drum, whereby the end faces of the stubs in those flutes which are controlled by the guides disposed at the greatest distance 35 from the periphery of the drum are engaged by a remaining guide or guides, a part at least of said remaining guide or guides being disposed in the path of the stubs engaged thereby, so that the stubs so engaged are spaced apart from each 40 other in the direction of their longitudinal axes. Stubs of comparatively long length may be delivered from a hopper to the feeding means, and cutting elements provided to subdivide the long lengths, whilst they are carried by said means. 45

The invention will be more particularly described with reference to the accompanying drawings, in which:—

Figure 1 is a vertical sectional view of stub feeding mechanism constructed in accordance 50 with the invention.

Figure 2 is a side elevation partly in section and drawn to an enlarged scale, showing a portion of the stub feeding mechanism illustrated in Figure 1.

Figure 3 is a view of Figure 2, looking in the direction of the arrow A.

Figure 4 is a side elevation of the mechanism illustrating gearing for driving the various rotating parts.

Figure 5 is a fragmentary sectional view on the line 5-5 of Figure 4, and

Figure 6 is a sectional view on the line 6-6 of Figure 2.

10 Like references refer to like parts throughout the various figures of the drawings.

Referring to the drawings, comparatively long lengths of stub material are contained in a hopper 1, from which the lengths of material are 15 deposited one at a time into the flutes 2 of a rotatable drum 3. The stubs are supported in the hopper by a fixed plate 100 and an oscillating plate 101. The plate 101 is pivoted at 102, and is oscillated by a cam 103. A cam follower 104 is 20 carried by one arm on a bell crank lever 105 which is pivoted at 106 to the frame of the machine. The cam follower is maintained against the cam 103 by a spring, not shown. To the other arm of the bell crank lever 105 there is connected a link 107 which link is also connected to the plate 101. The action of the plate 101 is to 25 vibrate the stubs in the hopper 1 in order to facilitate the feeding of the stubs through the space 108 formed between the end of the plate 101 and the surface of the stationary support 100. It is 30 found that if such a plate as 101 is not used there is sometimes a tendency for the stubs to become jammed in the hopper, and not freely to pass through the opening 108. The drum 3 is divided 35 to enable knives 4 to sever the comparatively long stubs, as seen clearly in Figure 3, into three stubs of double the length required in the finished cigarettes. The knives 4 are circular rotating knives carried by arms 5, adjustably mounted on 40 a spindle 6. The knives are rotated in any suitable manner from the main drive of the machine, and grinders 7 are provided to sharpen both sides of the knives.

Guides 8 and 9 are provided to retain the stubs 45 in the flutes 2 of the conveyor, that is the drum 3, and the guides are so arranged that they are disposed at varying distances from the periphery of the drum. It will be seen from Figure 2 that the guide 9 is closer to the periphery of the drum 3 than is the guide 8. The guide 9 is positioned 50 to engage the middle severed stub, as can be seen from Figure 3, and as the drum 3 rotates, the outer stubs fall partly out of the flutes 2 and are engaged by the guide 8. The end faces of the 55 outer stubs are engaged by the guide 9, the edges 59 of which are formed as cam faces, and as the drum 3 continues to move the stubs past the cam faces and the guide 9, the outer stubs are moved away from the central stub so that the three stubs 60 are spaced apart from each other in the direction of their longitudinal axes. This permits the stubs to fall quite independently of one another and facilitates the transfer from the flutes 2 to the next conveyor as described below.

65 The stubs which have been spaced apart are deposited into the flutes 10 of a rotatable wheel 11 and in order to ensure that each stub is placed into the flutes 10, fork members 12 project through slots in the drum 3 and engage with and 70 ensure that three aligned stubs are removed from a flute 2 of the drum 3 and deposited into a flute 10 of the drum 11 which in turn delivers the stubs to the flutes 15 of a rotatable drum 16.

It is found that when the stubs are being spaced 75 apart in the manner just described, there is some-

times a portion of material projecting from an end of a stub, the projecting portion being entangled with the end of the adjacent stub. When such is the case, the stubs, when being spaced apart in the direction of their longitudinal axes, are sometimes caused to be moved out of alignment with respect to the path through which they are intended to be carried by the drum 3, and in such cases it is necessary to re-align the stubs with the path through which the drum 3 is arranged to carry them, otherwise when they are placed upon a conveyor which moves the stubs into alignment with cigarette lengths, it is found that the stubs are not correctly deposited on the conveyor. In order to avoid this difficulty, the 10 stubs in the flutes 15 are moved in the direction of their longitudinal axes and towards the central point of their combined overall length, the central point being considered when the stubs are correctly aligned with respect to the path 15 through which the drum 3 is arranged to carry the stubs. The means to effect this operation comprises a pair of guides 13 and 14 which are bell-mouthed where the stubs first engage with the guides, and the guides 13 and 14 gradually 20 converge towards each other until they are in alignment with the drum 3, and are spaced apart in a manner such that the stubs are completely closed together so that they abut end to end and are again conveyed in the same general path as that through which the drum 3 previously conveyed the stubs.

After the stubs being conveyed by the drum 16 have been closed together they are again spaced 25 apart in the direction of their longitudinal axes whilst being controlled by guides 17, 18 and 19, the guides 17 and 19 being disposed at a distance from the periphery of the drum 16 which is greater than the distance between the periphery of the drum and the guide 18. The guide 18 is provided 30 with edges 58 formed as cam faces as above described with respect to the guide 9, and the inner end faces of the outer stubs which stubs are controlled by the guides 17 and 19 respectively are 35 engaged by the cam faces of the guide 18, the outer stubs being thereby moved in the direction of their longitudinal axes so that the stubs are spaced apart. This second separation serves to 40 facilitate the fall of the stubs from the drum as 45 in the previous case, and also more accurately locates the stubs and spaces them apart axially.

It will be appreciated that if desired the separation of the stubs may be effected in a plurality of stages by suitably modifying the shape of the 50 cams 9 and 18.

The stubs are delivered from the drum 16 to 55 control means formed as stub arresting surfaces. As the stubs leave the flutes 15 they roll over inclined surfaces 21 and 22, the surface 22, which 60 engages with the central stub, being arranged slightly in advance of the surfaces 21 over which the outer stubs pass, the arrangement being clearly shown in Figure 2 and such as to obtain the free delivery of the stubs from the flutes to the 65 controlling means.

The stub arresting surfaces 20 comprise three movable members, one for each of the three stubs, delivered by a flute 15, and the surfaces are arranged above the path of an endless conveyor 23 70 formed in the present case as a rotatable disc and provided with pusher pieces 24, each of which 75 engages with a stub to move the stub above a trough 25 in which the stub is deposited and inserted into the space between successive cigarette 75

lengths which are to be assembled with the stub in order to form mouthpiece cigarettes.

An annular space 26 is provided between the conveyor 23 and an outer wall 27, the stubs being moved through this space by the pusher pieces 24. The outer wall 27 is carried on a stationary supporting plate 28. The supporting plate 28 forms a bottom to the space 26 between the conveyor 23 and the wall 27, except at a place directly above the trough 25, a space being provided in the plate 28 at this point to enable the stubs to be deposited into the trough 25. The speed of the conveyor 23 is such that whilst one flute 15 is passing over the space 26, three pusher pieces 24 will move past the place at which the three stubs delivered by the flute are arrested by the surfaces 20.

The conveyor 23 and drum 16 may be driven in any convenient manner. For example, the sprocket *a* shown in Figures 1 and 4 is driven by gearing from the main shaft of the machine which drives the spindle on which sprocket *a* is mounted. Sprocket *a* is connected by a chain with a sprocket *b* to which a gear *c* is fixed, the gear *c* intermeshing with a gear *d* mounted on the spindle *e*. To the near end of the spindle *e* is secured a gear *f*, Figure 4; the gear *f* intermeshes with a gear *g* to which is secured a smaller gear *h* which in turn intermeshes with a large gear *j* carried on the spindle *k* on which the drum 3 is mounted.

A smaller gear *m* is mounted on a shaft *n* and intermeshes with the large gear *j*, and another gear *p* is also mounted on the spindle *n* and intermeshes with a gear *q* mounted on the spindle *r* of the fluted drum 16. A gear *s* is mounted on the spindle *t* of the fluted drum 16 and intermeshes with the gear *q*.

The conveyor 23 is also driven from the shaft 40 which carries the sprocket *a*, and is driven by intermeshing gears *u* and *v*, the gear *v* being mounted on the same shaft as the sprocket *a*. The gearing above described is so arranged that three pusher pieces 24 pass the delivery point 45 while the drums 3, 11, and 16 each move a distance of one flute.

In order to allow each of the stubs to be fed in turn on to the supporting plate 28, each of the arresting surfaces 20 are moved into and out of the path of the stubs by means of levers 29 which are operated by cams 30, a spring 31 being provided to maintain the parts in their working position.

Above the stubs supported by the stub arresting surfaces 20, there are provided three stub engaging elements 32, each of which is arranged to engage with one of the stubs delivered by one of the flutes 15. The stub engaging elements are pivoted at 33, and are operated in timed relationship with the stub arresting surfaces 20. The stub engaging elements 32 are provided with tail-pieces 34, which protrude through slots in the arresting surfaces 20, and the tail pieces are engaged by stops 35 secured to the arresting surfaces. As the lobes 51 of the cams 30 cause the arresting surfaces 20 to be withdrawn out of the path of the stubs so as to allow them to be deposited upon the supporting plate 28, each of the stops 35 engages with the corresponding tail piece 34, and causes the respective stub engaging element 32 to be pivoted about the point 33 so that it moves downwardly and engages with the stub upon the supporting plate 28, and ensures that the stub is positioned on the supporting plate

before the stub is engaged by a pusher piece 24. The stub engaging element 32 ensures that the stub is in position on the supporting plate 28, and that it does not rebound after falling on to the plate, thereby tending to assume an undesired position.

When three stubs are positioned above the space 26, they are allowed to fall at predetermined intervals so that they are engaged in succession by one of the pusher pieces 24, and in the example 10 shown in the drawings, the central stub is the first to be deposited upon the plate 28, whereafter the two outer ones are deposited one after the other.

What I claim as my invention and desire to secure by Letters Patent is:—

1. In a machine for manufacturing mouthpiece cigarettes, a conveyor for a plurality of axially aligned stubs, two or more of said stubs being in abutting relation to each other, and means to alter the relative positions of the abutting stubs 20 on the conveyor to space the stubs apart in the direction of their longitudinal axes.

2. In a machine for manufacturing mouthpiece cigarettes, a conveyor for a plurality of substantially axially aligned stubs, two or more of said 25 stubs being in abutting relation to each other, and means to engage an end face of a stub on the conveyor and to move the stub in the direction of its longitudinal axis and space it apart from an adjacent abutting stub on the conveyor. 30

3. In a machine for manufacturing mouthpiece cigarettes, a conveyor for a plurality of axially aligned stubs, means to effect displacement of the stubs in a direction transverse to the longitudinal axes thereof, and means to engage an end face 35 of a displaced stub and to move that stub in the direction of its longitudinal axis to space it apart from contacting relation with an adjacent stub.

4. In a machine for manufacturing mouthpiece 40 cigarettes, a conveyor to move a plurality of axially aligned stubs in a direction transverse to their longitudinal axes, and means to alter the relative positions of the stubs on the conveyor to space the stubs apart in the direction of their 45 longitudinal axes.

5. In a machine for manufacturing mouthpiece cigarettes, a conveyor to move a plurality of substantially axially aligned stubs in a direction transverse to their longitudinal axes, and means 50 to engage an end face of a stub on the conveyor and to move the stub in the direction of its longitudinal axis and space it apart from an adjacent stub on the conveyor.

6. In a machine for manufacturing mouthpiece 55 cigarettes, a conveyor to move a plurality of axially aligned stubs in a direction transverse to their longitudinal axes, means to effect displacement of the stubs in a direction transverse to the longitudinal axes thereof, and means to 60 engage an end face of a displaced stub and to move that stub in the direction of its longitudinal axis to space it apart from contact with an adjacent stub.

7. In a machine for manufacturing mouthpiece 65 cigarettes, a conveyor to move a plurality of substantially axially aligned stubs in a direction transverse to their longitudinal axes, means to effect spacing of the stubs in the direction of their longitudinal axes in a plurality of stages, and 70 means operative between successive stages to move the stubs in the direction of their longitudinal axes and toward the central point of their combined over-all length, said first named means comprising elements to engage an end face of a 75

stub and move the stub in the direction of its longitudinal axis.

8. In a machine for manufacturing mouthpiece cigarettes, a conveyor to move a plurality of substantially axially aligned stubs in a direction transverse to their longitudinal axes, means to effect spacing of the stubs in the direction of their longitudinal axes in a plurality of stages, and means operative between successive stages to move the stubs in the direction of their longitudinal axes and toward the central point of their combined over-all length, said first named means comprising a device to effect displacement of the stubs in a direction transverse to the longitudinal axes thereof, and elements to engage an end face of a stub and move the stub in the direction of its longitudinal axis.
9. In a machine for manufacturing mouthpiece cigarettes, a conveyor to move a plurality of substantially axially aligned stubs in a direction transverse to their longitudinal axes, means to effect spacing of the stubs in the direction of their longitudinal axes in a plurality of stages, elements to engage an end face of a stub and move the stub in the direction of its longitudinal axis, and means operative between successive stages to engage the end face of the stub opposite that end face which is engaged by said

elements, to move the stubs in the direction of their longitudinal axes and toward the central point of the combined over-all length of the stubs.

10. In a machine for manufacturing mouthpiece cigarettes, a rotatable drum having peripheral flutes extending in a direction substantially parallel to the axis of rotation of the drum, a flute being arranged to contain a plurality of substantially axially aligned stubs, and means to alter the relative positions of the stubs in a flute to space the stubs apart in the direction of their longitudinal axes.

11. In a machine for manufacturing mouthpiece cigarettes, a rotatable drum having peripheral flutes extending in a direction substantially parallel to the axis of rotation of the drum, a flute being arranged to contain a plurality of substantially axially aligned stubs, a guide for each stub contained in a flute, said guides being so arranged that alternate stubs are displaced in a direction transverse to the longitudinal axes of the stubs, the edges of the guides controlling the remaining stubs, being arranged to engage an end face of a displaced stub and so shaped as to move the displaced stubs in the direction of their longitudinal axes.

ARTHUR BINGHAM.
